ABSTRACT: The invention relates to a circular piston combustion engine having a housing composed of at least one shell and heads parallel to each other, each shell being arranged between two heads and enclosing a chamber in which a piston is rotatably arranged, and coolant passages being provided in the heads, communicating with a sump attached to the bottom of the housing.

CIRCULAR PISTON COMBUSTION ENGINE

In reciprocating piston combustion engines, tight attachment of the oil sump presents no difficulties, since the crankcase is open at the bottom and its bottom edge lies in a plane, so that a good seal between sump and crankcase can be achieved with a flat gasket. In circular piston combustion engines, on the other hand, there is no open crankcase, and construction of the engine housing so that its bottom lies in a plane would require additional material, owing to the substantially oval shape of the housing, thus increasing weight and space requirements.

The object of the invention is to provide a circular piston combustion engine of the aforementioned kind wherein the attachment of a sump for the cooling liquid is simplified and a dependable seal is obtained. This object is accomplished, according to the invention, in that the passages in the heads terminate in a common plane at the bottom of the housing and in that the sump consists of a self-contained unit bolted along its periphery to the housing and having on top an opening for each head, communicating with the passage in that head and encircled by a packing ring which, when the fastening bolts are tightened, tightly encircles the mouth of the passage in the head.

Whereas in the conventional construction and arrangement for reciprocating piston combustion engines a gasket must be provided all the way around the sump, with a correspondingly long sealing length, the tightening of which requires a great many closely spaced bolts, in the proposal according to the invention sealing is provided only at the points where the cooling liquid leaves the heads, by placing simple packing rings around the mouths of the passages in the heads. These packing rings are compressed when the sump is bolted on, where owing to the short sealing length of each ring a comparatively small number of bolts suffices for a dependable fastening and seal.

The openings in the top of the sump are preferably provided with a rolled edge around which the packing ring is placed. This considerably simplifies assembly.

Preferably, a suction cage is arranged in the sump, its suction line terminating in one of the openings in the top of the sump, the passage corresponding to this opening in the head in question serving as suction passage for a circulating pump. Thus, the sump becomes a complete component with all openings and fittings required for return of cooling liquid from the several heads to the cooling liquid circulating pump.

An embodiment of the invention will now be explained by way of example with reference to the drawing. In the drawings:

FIG. 1 shows a partial longitudinal section through the housing of a treble circular piston combustion engine at the line 1—1 in FIG. 2; and

FIG. 2 shows a section at the line 2—2 of FIG. 1.

The housing of the circular piston combustion engine shown consists of outer heads 1 and 2 and inner heads 3 and 4. Between neighboring heads 1 and 3, 3 and 4, 4 and 2, jackets 5

are arranged, each having a multilobate inner surface 6 in the form of a bilobate epitrochoid and enclosing a chamber 6a. The housing is traversed by an eccentric shaft having a number of eccentrics corresponding to the number of jackets

5, on each of which a triangular piston is rotatably mounted. The pistons are oil cooled, the cooling oil being supplied to the pistons through passages in the eccentric shaft and returned through passages 7 in heads 2, 3 and 4. The passages 7 terminate in a common plane 8 at the bottom of the housing.

10 Heads 1, 2, 3 and 4 are provided with lugs 9 to which a self-contained oil sump 10 is bolted the top 11 of which has an opening 12 for each head 1, 2, 3 and 4, communicating with the passage 7 in that particular head. Each opening is provided with a rolled edge 13, encircled by a packing ring 14. When

15 the fastening bolts 15 are tightened, the packing rings 14 are deformed and provide a dependable seal. The pressing of the packing rings 14 against the bottoms of the heads is assisted by the concave shape of the top 11 of the sump 10.

In the oil sump 10, a suction cage 16 is arranged, whose suction line 17 terminates in an opening 18 in the top 11 of the sump 10, the passage 19 in head 1, matching this opening, being intended as a suction passage for a circulating pump not shown. The connection of the suction line 17 to suction passage 19 is likewise sealed with a packing ring 14.

20 The sump 10 consists of two sections 10a and 10b, rolled onto each other after insertion of suction cage 16 with suction line 17 and thus forming a self-contained unit. 20 designates a strut for the suction cage 16.

The invention may, of course, be employed likewise for circular piston combustion engines having only one shell, or more than three shells, by simply changing the dimensions of the oil sump and the number of openings in its top.

We claim:

1. A circular piston combustion engine having a housing 35 comprised of at least one shell and heads parallel to each other, each shell being arranged between two heads and enclosing a chamber in which a piston is rotatably arranged, and coolant passages being provided in the heads, communicating with a sump attached to the bottom of the housing, the

40 passages in the heads terminating in a common plane at the bottom of the housing, fastenable fastening means, the sump being a self-contained unit fastened to the housing along its periphery by said fastening means and having on its top an opening for each head communicating with the passage in that head and each opening encircled by packing means which, when the fastening means are tightened, sealingly encircles the mouth of the passage in that head.

2. A circular piston combustion engine accordingly to claim 1 wherein the edges of the openings are rolled up.

3. A circular piston combustion engine according to claim 1 wherein the top of the sump is concave.

4. A circular piston combustion engine according to claim 1 wherein a suction cage is arranged in the sump, its suction line terminating in an opening in the top of the sump, and the 55 passage matching said opening in the associated head serving as a suction passage for a circulating pump.
